SWITCH FOR DIRECTIONAL SIGNALS

Application filed March 6, 1929. Serial No. 344,812.

This invention relates to a switch for a directional signal, the general object of the invention being to provide switch means on the steering column operated by hand to close the circuits of the lamps in the signal device and operated by the movement of the steering wheel to open the circuits so that the device is semi-automatic, as the switches are opened by the movement of the steering wheel 10 in making the turn.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is a plan view of the steering wheel, showing the switch means on the column.

Figure 2 is a section on line 2—2 of Figure 1.

Figure 3 is a view taken a quarter turn from Figure 2, and showing parts in section.

Figure 4 is a section on line 4—4 of Figure 3.

Figure 5 is a sectional view through the switch casing, with one of the switch means in elevation.

Figure 6 is a vertical sectional view through the switch casing, with one switch closed and the other open.

Figure 7 is a diagrammatic view of the circuits.

As shown in Figure 7, the switch is used to control the circuits of the signal lamps 3 and 3' which are arranged in a signal device in such a manner as to indicate that the vehicle is to be turned to the right when one lamp is lighted and to the left when the other lamp is lighted.

A circular switch casing 6 is placed on the steering column 7 under the steering wheel 8 and two pairs of arc-shaped blocks

9 are placed in said casing. Each pair is slidably supported on the rods 10 and springs 11 are placed on the rods and act to press the blocks toward each other. The lower block of each pair carries a bridging member 12 which, when the block is in lowered position, will bridge the contacts 13 and 14 so that current will pass from one contact to the other. The contact 13 is connected with a terminal 15 which is electrically connected with the battery of the car or other source of supply and the terminal 16 which is connected with one of the contacts 14 is connected by a conductor 17 with the lamp 3' and the terminal 16 for the other contact 14 is connected by the conductor 18 with the lamp 3. Thus when one of the lower blocks is depressed, the circuit from battery B to one of the lamps is completed and when the other lower block is depressed, the circuit to the second lamp is completed.

A pair of shafts 19 is journaled in the casing 6 and a block 20 is fastened to the inner end of each shaft adjacent one end of the block and a handle 21 is fastened to the other end of each shaft. When each handle is in horizontal position, the block 20 which is connected with the shaft of said handle is also in horizontal position, so that the springs will press the blocks 9 toward the block 20 and thus hold the block and the handle in horizontal position, it being seen that the blocks 20 are arranged between the blocks 9. When the driver is to make a turn to the left, he swings the handle 21 on the left side of the casing 6 upwardly, so that the block 20 which is connected with the shaft of said handle, is moved into vertical position, which depresses the lower block 9 and thus closes the circuit to the left hand lamp. When the steering wheel is turned to cause the vehicle to make the turn, a depending bracket 22, fastened to the steering wheel 8, will strike the handle 21 which is in raised position, and thus lower the same so that the switch will be opened and the circuit broken to the lamp. Of course, when a right hand turn is to be made, the other handle is moved into vertical position to cause its block to depress the other switch to close the circuit to the right hand lamp.

and then when the turn is being made, the bracket on the steering wheel will engage the handle and thus open the switch. As will be seen, the switches for the lamps are closed by hand, but they are automatically opened by the turning of the steering wheel to make the vehicle take the turn.

It is thought from the foregoing description that the advantages and novel features of the invention will be readily apparent.

It is to be understood that changes may be made in the construction and in the combination and arrangement of the several parts, provided that such changes fall within the scope of the appended claim.

What we claim is:—

In a motor vehicle, a switch casing located on the steering column thereof adjacent the steering wheel, a switch in the casing comprising upper and lower members, rods on which the members slide, spring means for forcing the members toward each other, a bridging member carried by the lower member, a pair of contacts bridged by said member when the lower member is depressed, a block arranged between the two members, a shaft passing through the casing and connected with the block adjacent one end of the block, a handle connected with the outer end of the shaft and extending upwardly when the switch is in closed position and a depending part on the steering wheel for engaging the handle when the wheel is turned to cause the same to move the switch to open position.

In testimony whereof we affix our signatures.

ELMER L. YOCUM.
RALPH T. WARDROP.
